UNITED STATES PATENT OFFICE.

MILLER REESE HUTCHISON, OF WEST ORANGE, NEW JERSEY, ASSIGNOR TO LOVELL-McCONNELL MANUFACTURING COMPANY, A CORPORATION OF DELAWARE.

DIAPHRAGM-HORN.

1,189,952.

Specification of Letters Patent.

Patented July 4, 1916.

Application filed May 11, 1911. Serial No. 626,491.

To all whom it may concern:

Be it known that I, MILLER REESE HUTCHISON, a citizen of the United States, and resident of West Orange, in the county of Essex and State of New Jersey, have invented certain new and useful Improvements in Diaphragm-Horns, of which the following is a specification.

This invention relates to alarm or signaling apparatus, and especially to devices capable of producing a loud, imperative note of considerable carrying power, and therefore excellently adapted for use on automobiles and other vehicles, boats, factories, and elsewhere.

In the present invention I produce a signaling device characterized by the employment of a flexible, endless actuator, provided with projections forming a suitable uneven actuating surface or face. This endless

actuator may be an articulated chain. It is preferably driven by power means, and preferably by an electric motor; and in the typical instance it passes around a drum or sprocket on the armature or drive shaft and around an idler, and performs its work to actuate the diaphragm at a point between the drive and the idler. The endless actuator may be driven positively or otherwise.

The positive drive will, generally speaking, give a more powerful signal. The actuating projections or cam teeth may be friction-reducing elements, such as the rollers of a roller-bearing chain. The actuation of the diaphragm or other part by the projections may be either positive or by virtue of centrifugal action. In the first instance it is preferred to support the flexible actuator opposite the region of engagement by a stationary rigid backing. In the other instance the endless actuator may be of such length as to be flung outward between its driving and idle supports so that its projections intercept and strike the diaphragm wear-piece

or other complementary member. This last construction enables the actuator to yield in a desirable manner in the event of interference between the diaphragm and an actuating projection.

Having thus briefly described my invention I now proceed to a particular description of certain of the possible embodiments thereof, reference being had to the accompanying drawings, wherein:

Figure 1 is a view partly in longitudinal

section and partly in elevation of one form of the signaling device, and Fig. 2 is a similar view of another form.

In the views, the numeral 1 indicates a suitable resonator-projector, and 2 a diaphragm, it being understood that the resonator is preferably so proportioned as to be synchronous with the natural or a prominent frequency of the diaphragm. The diaphragm is preferably held in a suitable case, 3, consisting of a front section 3 and a rear section 4. The base of the resonator is secured to the front section in line with the sound-emitting opening 5 therein. The diaphragm is preferably clamped in place at its margins by clamping portions 6, 7 of the case sections and cork washers or the like 8, 9, clamping bolts or screws 10 passing through registering openings in the parts.

The endless, flexible actuator is illustrated in different forms and relations in the views, being designated 11^b and 11^c. It is shown as cooperating directly with the diaphragm or a wear-piece 12 fixed thereon, but it will be understood that this is shown as a preferred and illustrated arrangement, and that another part may co-operate with the actuator to bring about the vibration of the diaphragm. Moreover, while I refer to and prefer to use a diaphragm held around its margins and vibrating its internal area, it should be understood that I am not limited in all the aspects of the invention to such form of vibratory sounding element.

In Fig. 1 I have illustrated a signal in which the diaphragm or the like is actuated by projections in the nature of rollers 17^b. Antifriction actuating devices of this or similar character possess certain advantages which render them desirable in various forms of signaling devices. Obviously wear may be considerably reduced, and in addition the tone may be purified because the sliding of metal on metal is eliminated and a rolling contact substituted. I have shown these rolling members mounted on a sprocket chain 11^b, but the carrier or actuator may be of any suitable kind. Where they are mounted on an endless actuator, the wheels 13^b and 14^b will be suitably formed to correspond therewith. It will be understood that these roller projections are rotatable about the pivot pins 26 connecting the links of the chain and that they are of such diameter as 110

2
to project beyond the outer side of the chain into engaging relation with the wear-piece 12 or other thrust-receiving part. In this instance the backing member 20^b is preferably also an antifriction device. For purposes of illustration I have shown it as a roller whose shaft or journals are mounted in a suitable support 30. The bearings therein may be slotted and a backing screw or screws 21 may permit of adjustment.

Fig. 2 is illustrative of an assemblage in which the endless actuator operates the diaphragm by virtue of centrifugal force. The actuator 11^c may be positioned so that if drawn straight between the supports, it would not intersect the thrust-receiving part or anvil, such as 12, centrifugal force being relied on to bring the members into actuating relation. The action of centrifugal force may be best availed of when the actuator and its projections have considerable weight and inertia, when the rotary supports 13^c and 14^c are comparatively close together, and when the chain is comparatively loose so as to afford some slack between the supports. Such a signal will operate with fair efficiency without a backing member for the working course of the actuator, and will yield advantageously to neutralize the effect of any interference that may occur. Furthermore, the sound will be softened because the diaphragm is actuated

in a yielding manner, such softened tone being desirable for certain purposes. The softening and purifying of the sound is increased by the use of rolling projections 17^b, which may be like those of the preceding form.

I claim:

1. In an alarm or signaling device, a diaphragm, and mechanical means for actuating the same including an endless flexible actuator and rolling actuating devices carried thereby.

2. In an alarm or signaling device, the combination of a diaphragm, an endless flexible actuator provided with rolling actuating projections, and a thrust-receiving member adapted to be contacted by said projections to produce the vibration of the diaphragm.

3. In an alarm or signaling device, a diaphragm, an endless flexible actuator provided with rolling projections for causing the diaphragm to vibrate, and a rolling backing member for holding the actuator to its work.

Signed at New York city, in the county of New York, and State of New York, this 9th day of May, A. D. 1911.

MILLER REESE HUTCHISON.
